CLAIM

The ornamental design for a case for electronic devices, as shown and described.

DESCRIPTION

FIG. 1 is a front perspective view of a case for electronic devices showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view of the encircled portion of FIG. 1.

The dot-dash broken lines in FIGS. 1 and 9 delineate a portion of the case that is part of the claimed design and shown on an enlarged scale in FIG. 9. The dashed broken lines depict portions of the case that form no part of the claimed design. The claim extends to the solid lines comprising the pattern and surfaces bounded by the solid lines only. The portions of the case for electronic devices surrounding the pattern form no part of the claimed design.
